ATTYS

UNITED STATES PATENT OFFICE.

HARRY GUTMAN, OF OAK PARK, ILLINOIS.

TOBACCO-TREATING MACHINE.

Application filed November 26, 1920. Serial No. 426,478.

To all whom it may concern:

Be it known that I, HARRY GUTMAN, a citizen of the United States, and a resident of Oak Park, in the county of Cook and 5 State of Illinois, have invented a new and useful Improvement in Tobacco-Treating Machines, of which the following is a full, clear, and exact description.

My invention relates to improvements in 10 tobacco treating machines, and it consists in the combinations, constructions and arrangements herein described and claimed.

In preparing tobacco, it is generally customary to remove the stems and midribs of 15 the leaves, these stems and midribs being waste products. Heretofore it has been necessary to do this because if the stem or midrib is not removed, these parts being of harder texture will, if made up into cigars, 20 burn more slowly than the remainder of the leaf, thereby leaving glowing particles which project beyond the end of the consumed portion of the cigar, and are apt to fall on the smoker's clothing. Furthermore, the stems 25 or midribs, if wrapped up in a cigar, form unsightly hard strips when they happen to lie near the surface. These and other reasons have compelled manufacturers of tobacco heretofore to remove them prior to 30 their further use in making up tobacco for the trade. The removal of the stems and midribs of course necessitates machines for the purpose, and also operators to run them. Considerable time is consumed in the operation, 35 and it necessarily results in splitting the leaf.

An object of my invention is to provide a process of treating tobacco, whereby the necessity for removing the stems and midribs 40 of the leaves prior to their further use in manufacturing cigars, smoking tobacco, and the like, is obviated, thus effecting a considerable saving, not only in the cost of manufacturing the article, but also in time saved in the 45 operation.

A further object of my invention is to provide a process by means of which the stems and midribs are crushed so as to spread them out to a thickness equal to that of the main 50 body portion of the leaf, spreading apart the fibers of which the stems and midribs are

composed, so as to bring them into a comparatively loose state, in which they will burn at substantially the same rate as the remainder of the leaf.

A further object of my invention is to provide a process of treating tobacco, in which the stems and midribs hitherto considered as waste products may be utilized.

A further object of my invention is to provide a device by means of which the stems and midribs of the leaves are crushed, as described, without affecting the body portion of the leaf.

A further object of my invention is to provide a machine of the type described for treating tobacco, having crushing rollers which may be adjusted to insure the crushing of the stems and midribs, while leaving the body portion of the leaves intact.

Other objects and advantages will appear in the following specification, and the novel features of the invention will be particularly pointed out in the appended claims.

My invention is illustrated in the accompanying drawings, forming part of this application, in which—

Figure 1 is a view of one side of the device,

Figure 2 is a view of the opposite side, 80

Figure 3 is a plan view,

Figure 4 is a sectional view of a portion of the device,

Figure 5 is a side view of a portion of the device.

In carrying out my invention, I provide any suitable base, such as the legs 5. Mounted on the base is a frame having a bottom portion 6 to which are secured side portions 7 preferably made of sheet metal. The side 90 portions 7 are integral with a flat top plate 8 which extends beyond the side portions, as shown in the drawing, and which is bent downwardly at 9 to constitute an end portion 10, the lower end of the portion 10 being 95 secured to the bottom 6. The plate 8 constitutes a table and is provided with an opening 11 (see Figure 3), and is stamped or otherwise provided with a groove 12, of the shape shown in Figure 3, disposed along the 100 central axis of the table contiguous to the opening 11. As will be seen from Figure 4,

that portion of the top plate 8 which forms one edge of the opening 11 is beveled to form a stripping blade 13. Adjacent to one end of the device is secured a delivery plate 14.

- Carried by the bottom portion 6 are uprights 15, in which is journaled a lower shaft 16 extending transversely of the device. One end of this shaft is provided with a pulley driven by a belt 18. This shaft 16 bears a gear 19 which is in mesh with a gear 20 on the shaft 21. The latter shaft is disposed transversely of the device in the same vertical plane with the shaft 16. Bearing sleeves 22 are disposed in slots 23 in the uprights 15, these sleeves being vertically slideable in the slots. Secured to the lower shaft 16 is a crusher wheel 24, which extends to the upper edge of the opening 11, where it is in normal contact with a companion wheel 25, disposed on the upper shaft 21. The bearing sleeves 22 are held normally in a lower position, so as to permit the crusher wheel 25 to touch the crusher wheel 24, when there is nothing between them. As will be seen from Figures 4 and 5, the side uprights 15 have rods 26 extending upwardly through the bottom of a spring housing 27, which contains a spiral spring 28. The latter bears at its upper end on a washer 29 which is held by a nut 30 on the threaded end of the member 26. Secured to the bottom of the spring housing are downwardly extending shoes 31 which engage the bearing bushings. As will be seen from Figure 3, there is one of these spring housings 27 on each side of the upper crusher wheel 25. Secured to the uprights 15 is a frame 32 which bears a stripping member 33, whose end is disposed in close engagement with the upper crusher wheel 25.

From the foregoing description of the various parts of the device, the operation thereof may be readily understood. The apparatus is set in motion, and the leaves are fed between the crusher wheels, the midribs and stems passing along the groove 12 and between the crusher wheels. The upper crusher wheel is held by a spring tension 50 which is regulated so as to cause the wheels to crush the midribs and the stems, thus breaking apart the fibers, mashing the fibers to the thinness of the body portion of the leaf, but not crushing the body portion 55 itself. The leaf will either adhere to the upper or lower crusher wheel. Should it adhere to the lower crusher wheel, it is stripped therefrom by the stripping edge 13, whereas if it adheres to the upper crusher 60 wheel, it is stripped therefrom by means of the stripper 33. In any event the leaf is stripped from the crusher wheel and deposited on the delivery plate 14. The leaf may now be used, as, for instance, for the purpose

of providing a filler for cigars, and it will 65 not have the defects which it might otherwise have were the leaf not treated by the present device. All portions of the treated leaf will burn at substantially the same rate, and the leaf will not have the hard tough 70 vein-like portions, which render the tobacco unsightly when made up in certain forms, as, for instance, cigars.

In case the tension should be too great, so as to crush a portion of the leaf, as well 75 as the stem and midrib, the tension may be decreased until such a point is reached that the pressure of the springs will cause the upper crusher wheel 25 to crush the stem and the midrib, without injury to the leaf itself. 80

It will be understood that the gears 19 and 20 are always in mesh, but that the upper crusher wheel 25 moves slightly whenever a leaf is being passed through. This slight movement of course is also experienced by 85 the gear 20, but it is not enough to cause the disengagement of the gears, the movement being comparatively slight.

By the use of my invention, I can save the time and expense of cutting out the stems 90 and midribs of the leaves, and I really transform them so that they may be used with the rest of the stock.

I claim:

1. A tobacco treating machine, comprising 95 a slotted support, a shaft journaled in said support for revolution about a fixed axis, a crusher wheel carried by said shaft, a second shaft journaled in slots in said support 100 for movement toward and away from said first named shaft, spring means for normally forcing said second named shaft towards said first named shaft, a crusher wheel disposed on said second named shaft and arranged to engage said first named crusher 105 wheel, means for adjusting the spring tension on said second named shaft, a table having a central groove adjacent to the normally contacting surfaces of the crusher wheels, and a leaf stripping member associated with each of said crusher wheels. 110

2. A tobacco treating machine, comprising 115 a base, uprights carried thereby, each of said uprights being slotted, a shaft journaled between said uprights, a lower crusher wheel carried by said shaft, a table having an opening, one edge of said opening being beveled to constitute a stripper, the surface of the lower crusher wheel extending flush with the upper edge of said opening, a second shaft, bearings therefor slideable in said slots, an upper crusher wheel carried by said second named shaft, an extension carried by each of said supports, a spring housing surrounding each of said extensions, integral 120 extensions secured to said housing and arranged to engage the bearings of said second named shaft, a spring disposed in each 125

spring housing, means for adjusting the tension of each spring, and a leaf stripping member associated with said upper crusher wheel.

5. 3. A tobacco treating machine comprising a base, uprights carried thereby, a pair of shafts carried by said uprights, a crusher wheel carried by each shaft, a table having

a central groove adjacent to the normally contacting surfaces of the crusher wheels 10 and extending at right angles thereto, said table having an opening, one edge of the opening being beveled to constitute a stripper, and a second stripper carried by said uprights.

HARRY GUTMAN.
